UNITED STATES PATENT OFFICE.

GERTRUDE WAKEHAM, OF MARSHALL, WISCONSIN.

DESIGN FOR A SLED.

59,797.

Specification for Design.

Patented Nov. 22, 1921.

Application filed August 12, 1921. Serial No. 491,868. Term of patent 14 years.

To all whom it may concern:

Be it known that I, GERTRUDE WAKEHAM, a citizen of the United States, residing at Marshall, in the county of Dane and State of Wisconsin, have invented a new, original, and ornamental Design for Sleds, of which the following is a specification, reference being had to the accompanying drawing, forming part thereof.

In the drawings:

Figure 1 is a view of the sled in side elevation;

Fig. 2 is a view of the sled in front elevation, and

Fig. 3 is a view of the sled in top plan. The design comprehends spaced runners with certain frame-work connecting the runners and with the representation of a dog mounted on the runners.

I claim:

The ornamental design for a sled as shown and described.

GERTRUDE WAKEHAM.
